UNITED STATES PATENT OFFICE

HAROLD A. WHEELER, OF GREAT NECK, NEW YORK, ASSIGNOR TO HAZELTINE CORPORATION, A CORPORATION OF DELAWARE

ELECTRIC COUPLING CIRCUITS

Application filed August 20, 1930. Serial No. 476,542.

This invention relates to high frequency electric coupling circuits tunable over a range in frequency and adapted more especially for interconnecting successive elements of a high frequency thermionic amplifier or radio system.

The coupling circuits of the present invention are characterized in that the voltage amplification produced thereby is caused to vary automatically with the frequency of tuning in a manner which is under the control of the designer; the design in general being preferably such as to produce a substantially constant resultant amplification, i. e. uniform sensitivity throughout the tunable frequency range.

With an elementary type of high frequency coupling circuit of which a closely coupled two-winding transformer having a tunable secondary is a typical example, the variation in amplification with frequency is not under control of the designer; but increases with frequency throughout the tunable range, in a manner well understood, with consequent detrimental effects including extreme non-uniformity of amplification.

In the elementary type of coupling circuit referred to, there exists between the primary and tunable secondary circuits a degree of coupling which is substantially constant throughout the tunable range, a condition which is partially responsible for the mentioned increase in amplification with frequency. The coupling circuit of the present invention avoids the resulting disadvantages by proper inclusion of suitable reactance elements adapted to provide an effective coupling between the input and tunable output circuits which automatically decreases with increase in the tuned frequency, and which may be proportioned to offset wholly or in part the factors operative to produce an increase in amplification with frequency.

Coupling circuits broadly operative in accordance with the principles disclosed herein but differing from the present invention as regards both circuit connections and the specific modes of operation thereof, are set forth in Patent No. 1,763,380 issued to C. E. Trube, and in his copending applications Serial No.

101,906, filed April 14, 1926, and Serial No. 120,045, filed July 2, 1926.

The coupling circuits of the present invention embody the following essential elements, namely: a tunable secondary circuit including a fixed inductive winding and a variable tuning capacity bridge between a pair of output terminals, and a primary circuit including in closed series connection in the order recited, a fixed inductance magnetically uncoupled from said secondary winding, a primary winding magnetically coupled to the secondary, a fixed capacity, and a portion of the secondary winding of relatively few turns compared to the fixed inductance. One input terminal is connected at a point between the primary winding and a fixed capacity, and the other input terminal is connected at a point between the secondary winding and said fixed inductance, a terminal of the secondary winding being thereby connected directly to one input terminal.

Due to the manner of connecting the input terminals to the primary circuit a pair of parallel paths are provided therebetween, one of which contains the primary winding and the fixed inductance while the other path contains the fixed capacity and the mentioned portion of the secondary winding. The primary winding and the secondary portion included in the primary circuit are connected with opposite polarities relative to the input terminals.

An additional capacity may or may not be connected between the input terminals, or in the operation of the circuit, capacity may exist between these terminals due to the impedance of the input circuit connected thereto. Irrespective of the particular arrangement used, the resultant capacity associated with the inductance of the primary circuit, including the fixed capacity of the closed series connection as well as any capacity existing between the input terminals, should be such as to make the primary circuit resonant at a frequency lower but not greatly lower than the lowest frequency within the tunable range.

The objects attained by such design (1) provide an effective coupling between pri-

mary and secondary circuits which automatically falls off as the frequency of tuning is increased, but at a rate proportioned to produce a desired variation in amplification with frequency, and (2) control the variations of the input impedance of the coupling circuit throughout the tunable range in such manner as to insure the desired operation of the circuit.

10 The manner in which the results of the present invention are achieved will be more clearly understood upon detailed consideration of the circuit connections set forth in the drawing of which:

15 Fig. 1 shows in diagrammatic form the elementary coupling circuit of the present invention;

Fig. 2 shows the coupling circuit of Fig. 1 as utilized for connecting an antenna circuit to the input of a thermionic valve; while

20 Fig. 3 is a diagrammatic representation of the circuit of Fig. 1 as employed for interconnecting a pair of thermionic valves in cascade relation.

25 Figure 4 is a diagrammatic representation of a preferred arrangement of coil elements L_s and L for employing the natural capacity between said coils to provide capacity C_1 .

Like elements are similarly designated in 30 the several figures.

Referring to the drawing, the coupling circuit comprises a resonant secondary circuit consisting of a fixed inductive winding L and a variable tuning condenser C connected in 35 parallel between output terminals O ; and a primary circuit associated with input terminals I which includes in closed series connection in the order recited, a fixed inductance L_2 , a primary winding L_s magnetically coupled to the secondary, a fixed capacity C_1 and a portion L_1 of the secondary winding L , of

40 relatively few turns compared to L_2 . The input terminals I are connected respectively between the primary winding L_s and fixed capacity C_1 and between the fixed inductance L_2 and the portion L_1 of the secondary winding in such manner that the lower input terminal is connected to a terminal of the secondary winding.

45 50 The capacity C_2 , shown dotted, is intended to represent the entire capacity connected between the input terminals while the circuit is in operation. The largest inductance in the primary circuit is L_2 . This inductance combined with the other elements associated therewith, is resonant at a frequency lower but not greatly lower than the lowest frequency within the tunable range determined

55 60 by the adjustment of the tuning condenser C . It is not essential to the operation of the circuit that a capacity C_2 exist between the input terminals I . In the event that the capacity C_2 is zero, however, it is required that the

65 capacity C_1 be of such magnitude as to make

the primary circuit resonant at the low frequency above specified.

The elements of the primary circuit as thus proportioned assure that the path between the input terminals containing the elements C_1 and L_1 will be capacitively reactive and hence of decreasing impedance for increases in tuning frequency; whereas the path containing elements L_2 and L_s being inductively reactive, increases in reactance with the frequency of tuning. Thus it will be apparent that the windings L_1 and L_s produce effects in the secondary circuit which vary in opposite fashion with the tuning adjustment. The circuit including winding L_1 has its greatest effect at the higher tuned frequencies due to approach to series resonance between condenser C_1 and the relatively small effective inductance of winding L_1 . The circuit including winding L_s is most effective at the lower tuned frequencies as the result of approach to parallel resonance at the mentioned frequency below the tuning range of the primary circuit as a whole, i. e., windings L_2 and L_s , and the total capacity effectively in shunt thereto.

70 75 80 85 90 95 100 105 By properly proportioning these effects which vary oppositely with frequency and combining them in the secondary circuit in additive relation, a resulting effective coupling is attained between primary and tuned secondary circuits which may be caused automatically to decrease with increase in tuned frequency, in a manner which is under control of the designer, and which with sufficient accuracy is expressed by the following equation:

$$(1) \quad m = m_3 + \frac{m_4}{\left(\frac{f}{f_2}\right)^2 - 1}$$

110 where f is the frequency of tuning, f_2 is the resonance frequency of the primary circuit, and

$$(2) \quad m_3 = \frac{M_1 C_1}{C_1 + C_2}$$

$$(3) \quad m_4 = M_3 + \frac{M_1 C_1}{C_1 + C_2}$$

115 M_1 and M_3 are the mutual inductances between windings L_1 and L and between L_s and L respectively, while the symbols C_1 and C_2 have the significance indicated in the drawing.

120 125 130 135 140 The additive effects of windings L_1 and L_s upon the tuned circuit LC are obtained by connecting these windings in opposite open circuit polarity between the input terminals I . This reversal of connection is required to offset the substantial phase opposition of the primary circuit currents flowing in the paths $C_1 L_1$ and $L_s L_2$, respectively, resulting from the predominant capacitive reactance of the former and the inductive reactance of the

latter throughout the tunable frequency range.

In Fig. 2 the input terminals I of the coupling circuit are connected to an antenna 1 and ground 2 respectively, while the output terminals O are connected respectively to grid and cathode of a thermionic tube V. The capacity C₂ of Fig. 1 comprises in Fig. 2 the effective antenna-to-ground capacity which in conjunction with capacity C₁ makes the primary circuit resonant at the mentioned frequency below the tunable range.

In Fig. 3 the coupling circuit of Fig. 1 interconnects a pair of thermionic tubes V₁ and V₂ in cascade relation. The input terminals I are connected to anode and cathode of tube V₁, while the output terminals O are joined to grid and cathode respectively of the tube V₂.

The space current for tube V₁ is supplied from a battery B serially included in the shunt path containing elements L₂ and L₃, with the negative battery terminal connected to the grounded conductor 3.

The capacity C₂ of Fig. 1 comprises in Fig. 3 the anode-to-ground capacity of tube V₁, which, in conjunction with the capacity C₁ should be such as to tune the inductance of the primary circuit to the low frequency above specified.

Reverting again to Fig. 1, the capacity C₁ may be a physical condenser connected between windings L₃ and L, or winding L₃ may be placed in close proximity to winding L, as by winding the former about the latter, so that the natural capacity between windings will provide the necessary capacity C₁ for completing the primary circuit. In such event the lower terminal of winding L₃ would be connected only to the upper input terminal.

A preferred arrangement of coils L₃ and L, to secure natural capacity as C₁, is as follows. A layer of insulating material is placed over the winding L, and L₃ is wound thereon with the same direction and pitch of winding as used in L. The lower end of L₃ is just over the part of L where the tap would otherwise be connected, and the upper end of L₃ is toward the upper end of L. This structure is equally applicable to Figs. 1, 2 and 3.

Fig. 4 shows the physical arrangement of coil elements for employing the natural capacity between coils L and L₃ to provide the capacity C₁. Coil L, as shown, is wound in a single layer upon any suitable form of insulating material. Coil L₃ is in turn wound in a single layer upon and in the same sense with coil L. Coil L₂ which is formed is situated adjacent the high potential end of coil L with its axis intersecting the axis of coil L at right angles. This arrangement minimizes the magnetic coupling between coil L₂ and coil L.

The upper input terminal I is connected to

the high potential terminal of coil L₃, the low potential terminal of which is connected through the winding of coil L₂ to the low potential input terminal I in the manner shown in the schematic circuit of Fig. 1. 70 Winding L is connected between the output terminals O in parallel with the variable tuning condenser C.

It will be noted that in Figs. 2 and 3 the rotor element of the tuning condenser C is 75 adapted to be grounded directly, constituting a very desirable feature, in that it eliminates certain accidental undesired couplings between different parts of the entire circuit.

What is claimed is:

1. An electric coupling system comprising a tunable secondary circuit including a fixed secondary winding and a variable capacity bridged between output terminals; and a primary circuit including in closed series connection in the order recited, a fixed inductance, a primary winding magnetically coupled to said secondary, a fixed capacity and a portion of said secondary winding, 85 input terminals connected between said primary winding and said fixed capacity and between said fixed inductance and said secondary winding respectively, said fixed inductance together with associated capacity being resonant at a frequency slightly below 90 the tunable range, for controlling throughout said frequency range the resultant coupling between said primary and secondary circuits.

2. A high frequency electric coupling system comprising a tunable secondary circuit consisting of a fixed secondary winding and variable capacity bridged between output terminals; and a primary circuit including in closed series connection in the order recited, a fixed inductance, a primary winding magnetically coupled to said secondary, a fixed capacity and a portion of said secondary winding of relatively few turns compared to the said fixed inductance, input terminals connected between the said primary winding and fixed capacity and between said fixed inductance and secondary winding terminal respectively, said primary winding and secondary winding portion being connected with opposite polarities relative to said input terminals, and said fixed inductance together with associated capacities including any capacity effectively bridged between said input terminals in the operation of said circuit, being resonant at a frequency 110 slightly below the tunable range, for controlling throughout said range the resultant coupling between said primary and secondary circuits.

3. In a radio receiving system the combination of an electric coupling circuit comprising a tunable secondary circuit including a fixed secondary winding and variable ca- 125

3. In a radio receiving system the combination of an electric coupling circuit comprising a tunable secondary circuit including a fixed secondary winding and variable ca- 130

capacity bridged between grid and cathode of a therminonic valve, and a primary circuit including in closed series connection in the order recited, a fixed inductance, a primary winding magnetically coupled to the secondary, a fixed capacity, and a portion of said secondary winding of relatively few turns compared to said fixed inductance, input terminals connected between said primary winding and fixed capacity and between said fixed inductance and secondary winding respectively, and an antenna circuit connected to said input terminals, the inductance of said primary circuit together with the associated capacities including the capacity of said antenna circuit, being resonant at a frequency below the tunable range.

4. In a high frequency thermionic amplifier, the combination of an electric coupling circuit comprising a tunable secondary circuit including a fixed secondary winding and variable capacity bridged between grid and cathode of a first thermionic tube, and a primary circuit including in closed series connection in the order recited, a fixed inductance, a primary winding magnetically coupled to said secondary, a fixed capacity, and a terminal portion of said secondary winding, of relatively few turns compared to said fixed inductance, a second thermionic tube having an anode connected between said primary winding and fixed capacity and a cathode connected between said fixed inductance and secondary winding terminal, and said fixed inductance together with the associate capacities including the anode-to-ground capacity of said second thermionic tube, being resonant at a frequency slightly lower than the lowest frequency within the tunable range, for providing throughout said frequency range uniformly high amplification in the operation of said system.

In testimony whereof I affix my signature.
